UNITED STATES PATENT OFFICE.

ARTHUR K. SMITH, OF ST. LOUIS, MISSOURI, ASSIGNOR TO CUTLER MAIL CHUTE COMPANY, OF ROCHESTER, NEW YORK, A CORPORATION OF NEW YORK.

MAIL-CHUTE.

1,145,443.

Specification of Letters Patent.

Patented July 6, 1915.

Application filed May 26, 1910. Serial No. 563,583.

To all whom it may concern:

Be it known that I, ARTHUR K. SMITH, a citizen of the United States, residing at St. Louis, Missouri, have invented a certain new and useful Improvement in Mail-Chutes, of which the following is a full, clear, and exact description, such as will enable others skilled in the art to which it appertains to make and use the same, reference being had to the accompanying drawings, forming part of this specification, in which—

Figure 1 is a side elevation of my improved chute. Fig. 2 is a sectional view on the line A—A Fig. 1. Fig. 3 is a view similar to Fig. 2 showing the parts in another position. Fig. 4 is a view of my improved chute showing a modified form in horizontal section.

This invention relates to a new and useful improvement in mail chutes, the object being to so construct the chute that access may be gained to the interior for the purpose of repair or to remove any obstructions therein.

With this object in view the invention consists in the construction, arrangement and combination of the several parts all of which will be hereinafter described and afterward pointed out in the claims.

Numeral 1 indicates conventionally the vertical wall of the building to which my mail chute is to be attached in any suitable manner.

It is to be understood that my device is to be made in sections which are suitably fastened together, and placed in a vertical position in the building, some of the sections having suitable apertures for the insertion of mail matter.

Fastened to the wall or other part of the building in any suitable manner are the angle irons 2 and 3 placed oppositely to each other as shown in Figs. 2, 3 and 4, or in place thereof a single channel-iron might be used or any suitable form of structural material. In the form shown the angle irons 2 and 3 are connected together by plates 4.

Mounted pivotally in the flanges of the angle irons not attached to the building are the lock bolts 5, having at one end thereof a suitable device whereby the bolts may be manually turned as indicated at 6.

Suitably attached between the angle irons 2 and 3 are a number of wrought iron pieces 7 shaped as shown in Figs. 2, 3 and 4, having a concavely curved section 8 and having the

ends thereof bent at right angles to the general direction of its length to form flanges 9 and 10, which bear against the upstanding flanges of the angle irons 2 and 3.

At either side of the bent pieces 8 in proximity to the ends 9 and 10 are formed seats 11. 12 is a sheet of metal formed in the arc of a circle to correspond with the curvature of the piece 8 and having the ends thereof 13 and 14 crimped or pressed into the seats 11 of the piece 8, whereby this sheet metal is held in position to form one side wall section of the chute.

The body of the chute proper 15, is formed in the arc of a circle corresponding to the curvatures of the section 12 so that the interior of the chute is substantially cylindrical. The ends of the portion 15 of the chute are adapted to fit in the seats formed by crimping the ends 13 and 14 of the section 12 of the chute.

The portion of the chute 15 at the front side thereof is cut away as at 16 for a portion of its length and has attached thereto on either edge of the said cut away portion 80 suitably bent strips of metal 17 and 18 to form a seat for a glass panel 19, which is held in position in said seat by a suitable frame 20. In this frame 20 is an off-set containing a mail receiving aperture 21. 85 Closely, but loosely surrounding the body of the chute section 15 are straps or bands of metal 22 the ends of which are bent at points 23 and 24 to engage the outside faces of the upturned flanges of the angle irons 2 and 3. 90 These ends of the bands 22 have L-shaped slots 25 formed therein as shown in Fig. 1 which slots are of sufficient width to be engaged by the lock bolt 5 which is half cut away at the portions thereof passing through the ends of the band. By this means when the lock bolt 5 is turned into position shown in Fig. 1 with the segmental portion of said bolt closely fitting the vertical portion of the slot 25, the band 22 engages and holds the 100 chute section 15 with the ends thereof in the seats 11 formed in the chute section 12.

When, however, the bolt 5 is given a quarter turn so that the segmental portion 26 of the bolt 5 is in a horizontal position the band 22 105 may be drawn to the right in Fig. 2 to disengage the ends of the chute section 15 from the section 12 whereupon the section 15 may be rotated through 90° more or less to the position shown in Fig. 3, which presents the 110

open portion of said section to one side of its supporting means, and allows the operator to insert his hand or other device for the purpose of cleaning or removing any 5 obstructions in the chute.

It should be noted that the horizontal portion of the slot 25 in the band 22 is of sufficient length to allow of this lateral movement of the band.

10 In Fig. 4 is illustrated a slight modification of the device shown in Figs. 2 and 3. In this construction the band 22' does not engage the chute section 15' all around its periphery, but is of a larger circumference 15 than the chute to leave a space 27 between the band and chute when the chute is in closed position in engagement with the other section 12' of the chute, which in all respects is similar to the section 12 in the 20 preferred form. Pivoted to one of the angle irons 2' and 3' is a hasp 28 which is bent and curved as at 29 with an opening therein to engage a staple 30 on the chute section 15'. An ordinary padlock or other locking means is to be inserted in the staple 30. In this construction the padlock 30 being 25 unlocked, and the hasp raised to the dotted line position shown in Fig. 4, the chute section 15' may be moved laterally toward the 30 right in said figure, and thereafter turned through substantially 90° in the same manner as described in connection with the structure shown in Figs. 2 and 3. The construction shown in Fig. 4 is the same in 35 every respect to that shown in Figs. 2 and 3, except for the changes which have been stated.

I am aware that minor changes may be made in the construction, arrangement and 40 combination of the several parts of my improved mail chute without, in the least, departing from the nature and principle of my invention.

I claim:

45 1. In a mail chute, a fixed chute section, a movable chute section adapted to engage the fixed chute section, and a supporting band surrounding the movable chute section to limit its movement, the movable section being adjustable laterally of the fixed 50 chute section within said band.

2. In a mail chute, a fixed curved chute section, a movable curved chute section adapted to engage the fixed section, and a supporting band surrounding the movable section and limiting its lateral movement, the last mentioned section being bodily movable laterally and rotatable relatively to the fixed section within said band. 55

3. In a mail chute, a fixed chute section, 60 a movable chute section adapted to be seated against the fixed section, a supporting band surrounding the movable section, the last mentioned section being adjustable laterally with relation to the fixed section within 65 said band, and a bolt passing through the ends of the band.

4. In a mail chute, a fixed chute section, a movable chute section adapted to engage the fixed chute section, said movable chute 70 section being bodily movable laterally away from the fixed chute section and rotatable relatively thereto, and adjustable retaining means acting when in one position to hold the movable chute section in engagement 75 with the fixed chute section and when in the other position to permit lateral movement of the movable chute section a limited distance.

5. In a mail chute, a fixed portion, a bolt 80 rotatably mounted therein, having a portion thereof cut away, and a movable portion adapted to be seated on the fixed portion, a band surrounding said movable portion, one end of the band having a slot therein adapted to engage the cut away portion of the bolt. 85

6. In a mail chute, a fixed portion, a bolt 90 rotatably mounted therein having portions thereof cut away, a movable portion adapted to be seated on the fixed portion, a band loosely surrounding the movable portion, and having L-shaped slots in the ends thereof adapted to engage the cut away portions 95 of the bolt.

In testimony whereof I hereunto affix my signature in the presence of two witnesses, this 18th day of May, 1910.

ARTHUR K. SMITH.
